TELEPHONE SECURITY LOCK

Edwin C. Glass, Northbrook, Ill., assignor to Gregory Enterprises, Inc., Chicago, Ill.

Filed May 22, 1972, Ser. No. 255,961

Term of patent 14 years

Int. Cl. D14—03; D8—07
U.S. Cl. D26—14 A

FIG. 1

FIG. 2

FIG. 4

FIG. 3

FIG. 5

FIG. 1 is a front perspective view of a telephone security lock showing my new design, the broken line representation of the telephone is shown for illustrative purposes only;

FIG. 2 is an end view of the telephone security lock illustrated in FIG. 1;

FIG. 3 is a front side view of the telephone security lock illustrated in FIG. 1;

FIG. 4 is a sectional view taken along the line 4—4 of FIG. 3, in the direction indicated; and

FIG. 5 is a top plan view of my telephone security lock.

I claim:

The ornamental design for a telephone security lock, as shown and described.
